UNITED STATES PATENT OFFICE.

TRUELL F. EMERSON, OF SOMERVILLE, MASSACHUSETTS, ASSIGNOR, BY MESNE ASSIGNMENTS, TO WALTER M. LOWNEY COMPANY, OF BOSTON, MASSACHUSETTS, A CORPORATION OF MASSACHUSETTS.

COUNTER-DISPLAY CONTAINER.

Application filed June 24, 1921. Serial No. 480,111.

To all whom it may concern:

Be it known that I, TRUELL F. EMERSON, of Somerville, in the county of Middlesex and State of Massachusetts, a citizen of the United States, have invented a new and useful Improvement in Counter-Display Containers, of which the following is a specification.

My invention relates to a container in which goods may be packed, provided with a cover which may be used to form an easel stand for the container, so as to display the goods.

It will be understood by reference to the drawings in which—

Figure 1 is a side elevation showing the container in display position.

Fig. 2 is a longitudinal vertical section of the device arranged as in Fig. 1, and

Fig. 3 is a side elevation, partly in section, of the container with its cover in closed position ready for shipment.

Fig. 4 is a perspective view of my container.

A is the container itself which may be as indicated in the drawings a rectangular pasteboard box. B is the cover having side flanges C and end flanges C'. One side flange C only is shown, but both are alike. Both side flanges C have cut from them a V-shaped piece as at c and the cover is preferably scored or constructed with a weakened line across the top as at c' so that a portion of the cover may be readily bent back to serve as a vertical support B' for the container, the score line registering with the upper ends of cuts c. The scored or weakened transverse line c' is much nearer one end of the cover than it is to the other, so that the part B', which is to serve as an easel support, is about one-third or one-fourth part of the cover and will thus reliably serve its intended purpose without any securing member.

The shape of the cuts at c is immaterial, the purpose of the cuts being to allow the two parts of the flange to separate when it is desired to use the container as a display stand, the score line serving to show where the portion B' of the cover may be bent.

In practice the goods are packed in the container and the cover is then put on in the usual way as shown in Figs. 3 and 4. When the goods contained in the container are placed on sale the cover is removed and turned upside down or reversed and the container A is set into the cover as shown in Figs. 1 and 2. The end B' is then bent down at an angle to the bottom of the container so that it will form an easel support for one end of the container, and the container is then placed upon the counter so that the goods are displayed as upon an easel (see Fig. 2), or it may be bent way back against the body of the container.

If desired, one end of the container may be extended to form a flap a on which there may be advertising matter and the flap which is bent down for shipment may remain so or may be stood up, advertising matter being arranged on the flap accordingly.

The container may be of any convenient shape.

What I claim as my invention is:—

1. A container and a cover therefor provided with flanges, two opposite flanges of said cover being cut at opposite points thereof and at points much nearer one end of said cover than the other; whereby when said cover is removed from said container and reversed said container may be set into it and the smaller portion of said cover may be bent backward on a line between said cuts to form an easel support for one end of said container to display the goods therein.

2. In combination with a container, a cover therefor having flanges at two opposite sides thereof and at one end thereof, said opposite flanges having V-shaped cut-out portions at opposite points therein near one end thereof, the top portion of said cover having a weakened transverse line registering with the apexes of said cut-out portions so as to be adapted to be bent back along said weakened line; whereby said container may be set into said cover to rest against one end flange thereof and the smaller part of the cover may be bent backward to form an easel support for said container and the goods contained therein may be displayed.

3. A container and a cover therefor provided with flanges, two opposite flanges of said cover being cut at opposite points thereof and at points much nearer one end ⁶ of the said cover than the other; whereby when said cover is removed from said container and reversed said container may be set into it and the smaller portion of said

cover may be bent backward on a line between said cuts to form an easel support ¹⁰ for one end of said container to display the goods therein, said container having at one end thereof a flap extending therefrom and adapted to carry advertising matter.

TRUELL F. EMERSON.
